UNITED STATES PATENT OFFICE

WALTER F. ROLSTON, OF ROCKFORD, ILLINOIS, ASSIGNOR TO BURSON KNITTING COMPANY, OF ROCKFORD, ILLINOIS, A CORPORATION OF ILLINOIS

YARN-CARRIER GUIDE AND TRANSFER MECHANISM FOR STRAIGHT-KNITTING MACHINES

Original application filed January 20, 1926, Serial No. 82,388. Divided and this application filed October 8, 1928. Serial No. 310,963.

This is a division of my application Serial No. 82,388 filed January 20, 1926, Patent No. 1,767,480, for yarn changing mechanism.

The present invention relates to straight knitting machines and has more particular reference to mechanism for guiding the active yarn to the needles, holding the inactive yarns and changing the yarns

Among the objects of my invention are to provide an improved yarn-carrier guide and an improved transfer device. These improvements are factors in promoting finer knitting and in reducing wear and breakage of parts.

The present improvements overcome certain objections to certain straight type knitting machines by the provision of a novel yarn carrier supporting and guiding structure characterized in the preferred embodiment by a stationary yarn-carrier guide or rail positioned above the needle beds and providing exceptionally rigid, broad bearing surfaces on which to support and guide the active yarn-carrier. Through this yarn-carrier mounting, which will be more fully described hereinafter, the distributor eye and plow latch openers of the yarn-carrier are maintained with extreme accuracy in the proper proximity and relationship to the needles of both beds. By reason of absolute accuracy in travel of the yarn-carrier I am enabled to guide both the distributor eye and the points of the latch openers closer to the needles, thus allowing the use of needles with finer hooks or of smaller dimensions generally, and consequently to secure a finer quality of knitting. Also there is less wear because of the nature of the yarn-carrier mounting, and cause for breakage is reduced to a minimum.

Another advantage of this phase of my invention is that I am enabled to employ a simplified transfer device having supplemental yarn-carrier rails, one for each yarn-carrier, adapted to be moved respectively into alignment with the stationary rail and to facilitate the movement of any yarn-carrier back and forth upon and between the supplemental and stationary rails. Still another advantage is that the end of the stationary rail adjacent to the transfer device may overhang or ex-

tend beyond the needle bed such an extent as to provide a full mounting for the yarn-carrier before it starts to function, thus insuring against any disalignment tendencies or difficulties at the transfer or during the initial functioning of the yarn-carrier.

A further object of my invention has to do with the use of a plurality of yarn-carriers having yarns differing in material, weight, color or quality, and particularly in the knitting of a sutured fabric. While my invention is applicable to the knitting of any fabric with different yarns it is herein adapted to the knitting of a so-called split sole stocking in which a suture occurs between the sole which is knit with one kind of yarn and the top portion of the foot which is knit with another yarn. It is also especially applicable to the knitting of the high splice above the heel, this being a suture knitting, preferably with a yarn different from that employed in knitting the sole portion.

Still another object is to provide a simplified and improved mechanism which will be thoroughly practical for the purposes intended.

Other objects and attendant advantages will be appreciated by those skilled in this art as the invention becomes better understood by reference to the following description when considered in connection with the accompanying drawings, in which—

General construction

In the present case I have, for purpose of illustration merely, shown my improvements as applied to a straight knitting machine having opposed beds of needles and more particularly to one forming the subject matter of certain of my co-pending applications. For example, the particular bed structure and needle-operating mechanism shown herein is the subject of my application Serial No. 76,142 filed December 18, 1925; the transfer device in certain respects is part of my application Serial No. 681,989 filed December 21, 1923; and certain features of the yarn-changing mechanism are claimed in my application Serial No. 82,388 filed January 20, 1926, of which the present application is a division. It should be expressly understood, however, that my present improvements are in no way confined to use with the inventions disclosed and claimed in said applications. It should be understood, therefore, that those parts and devices disclosed herein not directly claimed or essential to the present invention, are intended merely for purpose of clarity in illustrating the present improvements.

The bed construction and needle operating mechanism shown in Fig. 1 will be briefly described. The bed plates 11 and 12 carry opposed beds of needles in the angular relation shown defining a throat, which is well known in straight knitting machine. On each bed plate is carried a series of spaced division plates 13 between which are mounted needle supports 14, needles 15, needle jacks 16, jack housings 17, and pattern levers 18. The needles are held down on their supports by filler springs 19 which in turn are retained in position by a sinker bed 21. The sinkers 22 are of the usual construction retained in position by a sinker cap 23. The sinker cam bar 24 and the needle cam bar slide 25 are adapted to be reciprocated for advancing and retracting the sinkers and needles. The pattern levers 18 are adapted to be actuated by pattern cylinders 26 for throwing the needles into and out of action as explained in my application first above-mentioned. The bed plates 11 and 12 are supported at each end or in any suitable manner by a frame structure one end 27 of which is shown in Fig. 2.

Yarn carrier guide

As described briefly above I have provided means for supporting and guiding the active yarn-carrier in extremely accurate relation to the needles, this being accomplished primarily by the provision of a stationary guide rail designated generally by 28 positioned above and parallel with the needle beds and extending beyond both ends thereof. This rail is preferably rectangular in cross-section with its longer sides in a vertical plane so as to provide comparatively broad bearing surfaces on which to support and guide the yarn-carriers. Said rail should be accurately located and rigidly supported with respect to the needle beds, this being accomplished, in the present instance, by a plurality of brackets 29 fixedly attached to one side of the rail and at their opposite ends fixed to the bed structure, these brackets being arched as shown in Fig. 1 to clear the parts below and being suitably spaced longitudinally of the bed to give proper support to the rail (only one bracket being shown in this instance).

In the preferred embodiment of my invention only a single yarn-carrier is in action at one time, the remaining yarn-carriers being held on the transfer carriage which will be presently described. These yarn-carriers being identical in construction a description of one will suffice. As shown in Figs. 1 and 2 the yarn-carrier proper designated generally by 31 is of the usual construction including the yarn distributer eye 32 and plow latch openers 33. The sides 34 of the yarn-carrier proper are turned up and fixedly attached through the agency of a coupling connection 35 to a slide block 36 fitted to slide on three faces of the stationary rail 28. Bearing plates or gibbs 37 and 38 engage the fourth side of the rail 28 and are attached to the block 36 so as to retain the latter on the rail without interference with the rail-supporting brackets 29, the bearing plate 38 being yieldingly held in position by springs 39 so as to impose a slight friction between the slide 36 and the rail and to insure proper seating of the slide on the rail.

The yarn-carrier slide is adapted to be reciprocated on the rail by means of a push-and-pull finger 41 adjustably attached to a driver head 42 mounted to slide on the rail 28 in a manner similar to the slide 36, except that a spring tension between the head and rail is not necessary. The driver head is in turn adapted to be reciprocated through the agency of a link 43 connected to the usual rocking lever (not shown) such as described in my application Serial No. 76,142 above mentioned or any suitable means for imparting reciprocating motion. The finger 41 has a downturned end 44 adapted to have pushing contact against an upstanding abutment 46 both attached to the yarn-carrier

slide 36 in spaced relation so as to allow a lost-motion connection between the driver head and slide. The driver head 42 will be reciprocated by the means described in my said pending application for moving the slide 36 from the rail 28 onto a supplemental rail 61 described hereinafter. Said supplemental rail 61, part of a transfer mechanism also described later, is adapted to be shifted laterally to move its yarn carrier out of registration with the rail 28 and position another supplemental rail with its yarn-carrier in registration with said rail 28 so that the latter yarn-carrier may be moved onto said rail and into action by the forward movement of the driver head 42. The lost-motion connection referred to allows for this change of yarn-carrier without interruption of the regular reciprocation of the driver head, the change being made, of course, at the transfer end of the stroke.

It will be observed that the end 47 of the rail 28 extends beyond the adjacent end of the needle beds a distance equal to or greater than the length of the slide 36, the purpose of this being to provide a full and substantial support for the slide and consequently the yarn-carrier before the latter actually starts to function. This is a distinct advantage in that there is no danger or tendency for the yarn-carrier to be displaced by reason of the transferring action or of disalignment conditions incidental to its mounting.

With the foregoing construction the yarn-carrier is so mounted and supported that its distributor eye will lay the yarn with extreme precision in the hooks of the needles and there is no danger or tendency for displacement either laterally or vertically. Likewise the plow latch openers are guided with extreme accuracy and may be positioned in closer proximity to the needles so as to improve their functioning without, however, danger of striking and breaking latches or failing to function by reason of displacement from such predetermined position.

Transfer device

The transfer device proper disclosed herein is an improvement on that disclosed in my second above-mentioned application and reference may be had to the latter which discloses mechanism for shifting the transfer carriage in step-by-step movements to perform the transfer operations. The mechanism referred to is adapted to move the translating bar 48 (Figs. 2 and 7) vertically in definite strokes either up or down, each stroke being for the purpose of shifting the transfer carriage one position for effecting a transfer operation which may or may not transfer a yarn-carrier according to the arrangement of the yarn-carriers. In this embodiment of my invention the translating bar 48 has a rack 49 meshing with a spur

gear 51 fixed to a shaft 52 which in turn is journaled in a suitable bracket 53 mounted on the frame 27 and which has fixed thereto a transfer carriage at present in the form of a wheel designated generally by 54. A brake band 55 embraces a drum 56 fixed to the shaft 52 as shown in Fig. 7. The ends of the brake drum are associated with a stationary lug 57 on the bracket 53 and connected thereto by a bolt 58 carrying a coiled spring 59 adapted to urge the band against the drum and thus impose friction on the latter so as to instantly stop the transfer carriage after each transfer movement imparted by the bar 48.

The transfer carriage is equipped to carry a plurality, four in the present instance, of yarn-carriers at circumferentially spaced points so that by rotative movement of the carriage it will position the yarn-carriers successively in alignment with the stationary rail 28. To this end I employ preferably a single supplemental rail 61 for holding each yarn-carrier on the transfer carriage, these supplemental rails being spaced circumferentially about the transfer carriage as shown in Figs. 4 and 8 and located offset from a radial plane so as to register or be positioned in longitudinal alignment with the stationary rail 28 by rotative movement of the transfer carriage. As shown in Fig. 2 the transfer carriage is slotted to receive one end of each supplemental rail; and suitable means may be employed for rigidly securing such rail to the carriage. This view also shows each supplemental rail extending into such proximity to the adjacent end of the stationary rail that a yarn-carrier slide may move from one rail onto another in either direction, it being manifest that when fully positioned on its supplemental rail the transfer carriage may be oscillated to withdraw one yarn-carrier from the position in alignment with the stationary rail and locate another yarn-carrier at such position so that it may be moved onto the stationary rail and into action. For convenience the yarn-carrier at the position in alignment with the stationary rail will be referred to hereinafter as the active yarn-carrier and those at the other positions spaced around the transfer carriage as the inactive yarn-carriers.

As described in my second above-mentioned application the transfer carriage will be operated to perform the desired transferring operations, that is, to move the different yarn-carriers in predetermined order to the active position in which the respective yarn-carrier may be moved into action by the driver head.

It will be manifest that the purpose of the several yarn-carriers is to carry different yarns so that each may be presented to the needles at the proper times. In the present machine I employ four yarn-carriers which

I have designated and will refer to as Nos. 1, 2, 3, and 4, this particular number being desired for the knitting of a split sole stocking although as above-mentioned a greater or lesser number of yarn-carriers might be employed on a transfer carriage of this character, or with my invention, according to the particular knitting problem at hand. It is customary to feed the yarn to the yarn-carriers from overhead and in Fig. 2 is shown a yarn 62 extending down directly to the No. 1 yarn-carrier which is in the active position on the stationary rail, and a second yarn 63 extending from its overhead source through an opening 64 in a guard plate 65, thence through the distributor eye of the No. 3 yarn-carrier, and thence through a holding element (which will be presently described) to the needles.

20

Yarn holding means

The purpose of the yarn holding means is to hold the yarns from the inactive yarn-carriers out of the path of the active yarn-carrier 25 and to so hold and retain the yarns that there will be no tangling or interference thereof with the yarn-carriers or other parts by reason of the transfer operations. This problem presents difficulties especially when one of 30 the yarns to be held emanates from the needle bed at an intermediate point as at a suture point when knitting a split sole stocking, or when three different yarns are used in knitting a sutured fabric of this kind, or when 35 three or more different yarns are used. While this phase of my invention is claimed in my application Serial No. 82,388, above mentioned, it is here shown and described because it serves to better illustrate an application of 40 the invention claimed herein to actual working conditions. In the present embodiment of this phase of my invention I employ a pair of primary holding elements in the form of hooks 66 and 67 disposed beneath the active 45 position of the transfer device, and more particularly at opposite sides of and in close proximity to the path of the distributor eye 32 of a yarn-carrier located at said active transfer position. The normal location of 50 these holding elements is clearly shown in Figs. 4 and 5, from which it will be seen that the hooked ends of such elements extend upwardly and inwardly into the path of the depressions at each side of the distributor eye nose and consequently, above the 55 point at which the yarn emanates from said distributor eye, also that said hooked ends are located intermediate the distributor eye (shown in dotted lines in Fig. 5) and the 60 point 68 at which certain inactive yarns leave the needles. It is apparent that the holding elements 66 and 67 are in the path of the 65 yarns extending between the point 68 and the distributor eye and that when the transfer carriage swings in either direction this yarn

will be intercepted and held by either one or the other of said holding elements according to the direction of the transfer movement. Inasmuch as the said holding elements are located at one side of the path of the yarn-carrier distributor eye in the active position the yarn so held will not interfere with the yarn-carrier in said active position. It will also be manifest that the held yarn will be taut from the point it leaves the needles to the respective holding element and thence through its yarn-carrier by reason of the usual or any suitable take-up device (not shown) employed overhead on the machine for this purpose. In the present embodiment of my invention the holding elements 66 and 67 are in the nature of guiding means adapted to engage an unsevered yarn extending from the fabric to a yarn-carrier in an idle or inactive position for the purpose of guiding, retaining or holding this yarn in such position that it will not interfere with the yarn of a yarn-carrier in the active position.

Said holding elements 66 and 67 are mounted so that they may be moved away from the normal position just described, preferably to a lowered position out of the path which the yarn describes in an arc by reason of the movement of the particular transfer carriage herein employed. In the present embodiment this is accomplished by fixedly mounting said holding elements 66 and 67 on one end of a lever designated generally by 69 which is pivoted at 71 on the bracket 53. Suitable means such as a spring 72 fixed at one end to the pivot screw 71 and bearing downwardly at 73 on the rear end of the lever serves to constantly urge the forward end of the lever upwardly to locate the holding elements 66 and 67 in the said normal position which is limited by the lever striking an adjustable stop 74 on the bracket 53.

By rocking said lever 69 to lower said holding elements the latter will be withdrawn from said arcuate path of the yarn so as to be inactive as regards intercepting any yarn passing laterally thereover during a transfer operation but without releasing any yarn or yarns held by such holding elements. The purpose of this is to permit one or more predetermined yarns being transferred to pass said primary holding elements and be intercepted and held by either of a pair of supplemental holding elements 75 and 76 which are suitably mounted, preferably in fixed position, in this instance on the end extensions of the sinker beds 21 and located substantially in the same transverse plane as the primary holding elements.

Any suitable means may be provided for withdrawing the primary holding elements from their normal position, such for example, as a cam 77 on the transfer carriage 54 adapted for actuating an extension 78 on the lever 69 for depressing the forward end of said

70

75

80

85

105

110

115

120

125

130

lever. One or more cams of this character might be employed on the transfer carriage for rocking the lever 69 at predetermined times to render the holding elements 66 and 67 operative or inoperative for engaging yarn being transferred at certain times. While this operation of the primary holding elements by movement of the transfer carriage is exceptionally simple and direct and lends itself particularly well to timing such operation by location of the actuating cam 77 in juxtaposition to the particular yarn-carrier whose yarn it is desired not to be engaged by the primary holding elements, nevertheless it should be understood that such holding elements or the equivalent might be automatically operated from any suitable source. It will be apparent, viewing Fig. 4, that when the primary holding elements are depressed the transferring yarn when swung in either direction in the path indicated by the arc 79, will be intercepted by either one or the other of the supplemental holding elements 75 and 76 according to the direction of the transfer.

The purpose of the supplemental yarn holding elements which are spaced farther from the center line or throat of the machine than the primary yarn holding elements is to hold a yarn at the transfer end of the bed farther away from the throat at either side thereof and in a position extending across the path of a hooked finger, of which there are two, designated by 81 and 82, which move with the driver head. The particular yarn so to be engaged by one of said hooked fingers is one which emanates from the needles, as at a suture point 83, Fig. 3. In this view the yarn 84, carried by the No. 2 yarn-carrier, extends across the path of the hooked finger 81 which is shown in a position close to the transfer end of the machine. Said hooked fingers are preferably attached to the driver head 42 and consequently, are mounted to travel on the stationary rail 28 with the same degree of accuracy as the yarn-carrier although separate therefrom. As the driver head travels forward, that is, to the left viewing Fig. 3, the hooked finger 81 will engage the yarn 84 and draw it to the outer side of a yarn-retaining element 85 which at present is in the form of a straight length of wire spaced inwardly from the inner edge of the adjacent sinker cap 23 just sufficient to allow a path for the point of the finger 81 and to provide with said edge of the sinker cap a narrow retaining groove for the yarn 84. This wire-retaining element 85 extends lengthwise of the bed from the transfer end to the suture point 83, as clearly shown in Fig. 3, and is turned inwardly at said transfer end so as to provide a converging mouth to facilitate entrance of the yarn into said retaining groove. A similar yarn-retaining element 86 is provided on the opposite bed

with which the hooked finger 82, which is similar to the finger 81, cooperates, both retaining elements 85 and 86 being suitably supported in a fixed position as, for example, by short curved arms 90 fixed to the adjacent sinker cap 23. It will be manifest from the foregoing that when a yarn is laid across the path of either hooked finger 81 or 82 as when such yarn is held by either the supplemental holding elements 75 or 76 respectively, such yarn will be drawn into the groove behind the respective retaining element 85 or 86, as the case may be, from the transfer end of the machine to the suture point, and will be so held in an out-of-the-way or inactive position while the knitting may be carried on with another yarn. An example of such knitting will now be given.

Knitting sutured fabric

My improvements are especially adapted for the knitting of any sutured fabric or any fabric in which different yarns are used separately in the knitting of a complete course, that is, in which each yarn knits only a portion of the course. These conditions are exemplified in the knitting of a split sole stocking, which will now be considered, this example being substantially the same as discussed in my co-pending application, Serial No. 681,989, in which the operation and control of a transfer device handling four yarn-carriers is described.

Referring to Fig. 10 and considering the knitting of an entire fashioned, seamless, split sole stocking, the No. 1 yarn-carrier is used for knitting the toe, bottom portion or sole of the foot, and the heel, the yarn being usually of a heavy grade and more durable than that used for the upper portion of the stocking. In knitting the top and bottom of the foot portion between the points 87 and 88 the No. 1 and No. 2 yarn-carriers will be used alternately, thus knitting a sutured fabric, the No. 2 yarn being of a different grade or quality from the No. 1 yarn; for example, in knitting a silk stocking the No. 2 yarn would be silk. The heel pocket, that is, between the points 89 and 91 will be knit with the No. 1 yarn in the usual manner. Following this the No. 3 yarn-carrier will be brought into action alternately with the No. 2 yarn-carrier for knitting the portion of a stocking known as the high splice up to the point 92. The No. 3 yarn may be either a heavy silk or an admixture of silk and cotton so as to give more durable wearing quality at this portion and yet present the same silky appearance as the leg portion of the stocking. The major portion of the stocking is then knit with the No. 2 yarn by round-and-round knitting, in this instance, the stocking being fashioned in the knitting. This knitting is carried to any suitable length, such as to the point 93, when the No.

4 yarn-carrier is brought into action. This yarn-carrier is generally for cotton yarn and knits what is known as a garter or boot top.

5 While the No. 1 yarn is being employed in round-and-round knitting of the toe the remaining yarns Nos. 2, 3 and 4 will emanate from the needle bed at the points 68 (Fig. 5), the No. 2 yarn (designated above by 84) being held by the supplemental holding element 75, and the Nos. 3 and 4 yarns (the former being indicated above by 63) being held by the primary holding element 66 and extending around the transfer device to their 10 respective yarn-carriers, these yarns being further guided in the recesses flanking the sides of the distributor eye noses of the preceding yarn-carriers.

15 After the toe has been completed the transfer carriage will oscillate one position in a clockwise direction, viewing Figs. 4 and 8, thus moving the No. 2 yarn-carrier to the active position shown in Fig. 8. At the initial transfer movement the No. 1 yarn 20 will be engaged in the primary holding element 67 and subsequently the cam 77 will depress the primary yarn-holding elements from their normal position as above described, in which position they will be held 25 while the No. 2 yarn-carrier is in the active position.

30 From this point on the actual knitting of the sutured fabric with the Nos. 1 and 2 yarn-carriers and the 2 and 3 yarn-carriers will 35 be better understood by reference to Fig. 9 which shows diagrammatically a plan of the front bed of needles designated by A—B and the back bed by C—D, also the location of the suture point 83 and the yarn-retaining 40 elements 85 and 86. Ordinary round-and-round knitting is from A to B, termed the forward stroke on the front bed, and from C to D, the backward stroke on the back bed.

45 On the first forward stroke of the No. 2 yarn-carrier from its said active position on the transfer carriage its yarn will be knit by the needles on the front bed from the suture point 83 to B and on the backward stroke on the back bed from C to 83, then on the next 50 forward stroke on the back bed from 83 to C and on the backward stroke on the front bed from B to 83. It will be understood that during this knitting the needles from A and D to 83 are held out of action by the pattern 55 mechanism which forms no part of the present invention. At the end of this backward stroke the transfer carriage will shift one position in a counter-clockwise direction, thus carrying the No. 2 yarn clear of the depressed 60 primary yarn-holding elements and into the supplemental yarn-holding element 75, and returning the No. 1 yarn to the active position. At this stage in the knitting the Nos. 1 and 2 yarns, 62 and 64 respectively, are as 65 shown in Fig. 3. On the next forward stroke

70 the hooked finger 81 which precedes the No. 1 yarn-carrier will draw the yarn 84 back of the yarn-retainer 85 so that this yarn will be held at one side of the throat as described above. The No. 1 yarn on this forward 75 stroke will knit on the front bed from A to the suture point 83, then on the backward stroke on the front bed from said point 83 to A, then on the next succeeding forward stroke on the back bed from D to 83, and finally 80 on the backward stroke on the back bed from 83 to D. At the end of this backward stroke the transfer carriage will shift again in a clockwise direction, thus hooking the No. 1 85 yarn under the primary yarn-holding element 67 and bringing the No. 2 yarn-carrier into the active position. This cycle will then be repeated until the end of the split sole portion designated by 88 is reached.

85 The heel pocket from 89 to 91 will next be knit in the usual manner by the No. 1 yarn-carrier, and at the finish the transfer carriage will oscillate in a clockwise direction so as to return the No. 2 yarn-carrier to the active 90 position.

95 The high splice from 91 to 92 will now be knit by alternating operation of the Nos. 2 and 3 yarn-carriers. The first operation in this particular example is to knit with the No. 2 yarn on the forward stroke on the front bed from 83 to B and then on the backward stroke on the back bed from C to 83. At the end of this backward stroke the transfer carriage will shift one position in a clockwise direction to bring the No. 3 yarn-carrier 100 into the active position. At the initial part of this transfer operation the No. 2 yarn will clear the primary yarn-holding elements which are held in the down position by the cam 77 and will be caught by the supplemental 105 yarn-holding element 76, thus drawing the No. 2 yarn (84) across the path of the hooked finger 82 so that on the next forward stroke said hooked finger will draw this yarn behind the retaining element 86 110 to retain it at the back side of the throat. On this forward stroke the No. 3 yarn knits on the back bed from D to 83, then on the backward stroke on the back bed from 83 to 115 D, then on the forward stroke on the front bed from A to 83, and finally on the backward stroke on the front bed from 83 to A. At the end of this backward stroke the transfer carriage shifts one position in a counter-clockwise direction to bring the No. 2 yarn-carrier 120 into the active position. At the beginning of this transfer operation the No. 3 yarn will be caught and held by the primary holding element 66, whereupon said holding element 125 will be depressed by the cam 77 and the No. 2 yarn will clear the primary holding element 67. The No. 2 yarn will start knitting on the forward stroke on the back needles from 83 to C, then on the forward stroke on the front bed from B to 83, then on the next succeeding 130

forward stroke on the front bed from 83 to B, and finally on the backward stroke on the back bed from C to 83. At the end of this backward stroke the transfer carriage will shift again one position in a clockwise direction, thus returning the No. 3 yarn-carrier to the active position. The cycle just described will be repeated until the high splice is finished.

10 Following this the leg portion and the garter top will be knit by round-and-round knitting with the Nos. 2 and 4 yarns, respectively. The functioning of the yarn-holding elements during the knitting of these two 15 portions of the fabric will be manifest from the foregoing description.

After completing the knitting of a stroke the last yarn carrier in operation is moved onto a rail on the transfer carriage and shifted thereby to an inactive position. During the following stroke of the head 42 away from the transfer carriage the needles of both banks will be projected and in the absence of yarn being fed to such needles the 25 latches will be closed so as to permit withdrawal of the needles through the loops, thereby casting or shedding off the loops and thus discharging the stocking.

It should be understood that the foregoing 30 illustrates merely a single embodiment of my invention and that changes and modifications may be made without departing from the spirit and scope of the invention as expressed in the appended claims, in which—

35 I claim:

1. In a straight knitting machine, in combination, opposed beds of needles defining a throat, a single rail having bearing faces for supporting and guiding a yarn-carrier slide, 40 means rigidly supporting said rail in a position above and parallel with said throat, a plurality of yarn-carrier slides each adapted to be reciprocated on the said bearing faces of said rail with its yarn-carrier supported in 45 predetermined relation to the needles, means for reciprocating any slide on said rail, and a transfer mechanism having a plurality of supplemental yarn-carrier rails each of the same cross-section as said stationary rail for 50 carrying a yarn-carrier slide and adapted to be respectively moved into longitudinal alignment with said stationary rail, whereby a yarn-carrier slide is adapted to be moved back and forth upon and between the stationary rail and any supplemental rail in 55 alignment therewith.

2. In a straight knitting machine, in combination, the needles, a single yarn-carrier rail supported in a stationary position above 60 the needles having bearing faces on which any one of a plurality of yarn-carriers is adapted to be reciprocated, a transfer mechanism having a plurality of supplemental yarn-carrier rails adapted to be respectively 65 moved into longitudinal alignment with the

stationary rail, and a yarn-carrier adapted to be supported on each supplemental rail and to be moved from the latter onto the stationary rail when in alignment therewith and to be reciprocated on said stationary rail.

3. In a straight knitting machine, in combination, the needles, a single stationary yarn-carrier rail positioned above the needles having bearing faces on which any one of a plurality of yarn-carriers is adapted to be reciprocated, a transfer carriage mounted to swing about an axis parallel with the stationary rail, supplemental rails circumferentially spaced about said axis and adapted by 75 rotative movement of the carriage to be successively positioned in alignment with the stationary rail, a yarn-carrier adapted to be carried on each supplemental rail, and means for moving each yarn-carrier from its supplemental rail onto the stationary rail when 80 in alignment therewith.

4. In a straight knitting machine, in combination, a single stationary yarn-carrier rail having bearing faces on which any one of a plurality of yarn-carriers is adapted to be reciprocated, a transfer carriage equipped with a plurality of supplemental yarn-carrier rails spaced in arcuate relation and adapted by oscillation of the carriage to be 90 respectively positioned in alignment with the stationary rail, a yarn-carrier adapted to be carried on each supplemental rail, and means for moving each yarn-carrier from its supplemental rail onto the stationary rail when 95 in alignment with the latter.

5. In a straight knitting machine, in combination, a bed of needles, a single stationary yarn-carrier rail positioned above and parallel with said bed having bearing faces on which any one of a plurality of yarn-carriers is adapted to be reciprocated, a transfer device at one end of the needle bed having a plurality of supplemental rails each adapted for carrying a yarn-carrier, said transfer device being adapted for moving each supplemental rail into alignment with the stationary rail, a yarn-carrier for each supplemental rail, and means for moving each yarn-carrier from its supplemental rail onto the stationary rail when in alignment therewith and for reciprocating such yarn-carrier on said stationary rail, the stationary rail at its end adjacent to the transfer device extending beyond the needles at said end a distance substantially equal to the length of any yarn-carrier mounting on the rail whereby such yarn-carrier will be wholly supported on the stationary rail before it is brought into active cooperation with the needles.

6. In a straight knitting machine, in combination, a single guide rail having bearing surfaces on which any one of a plurality of yarn-carriers is adapted to be reciprocated for distributing yarn to the needles, and a transfer mechanism having a plurality of 125

guide rails each adapted to carry a yarn-carrier and to position any selected yarn-carrier in registration with the single guide rail so that the selected yarn-carrier may be moved back and forth upon and from one guide rail to the other.

7. In a straight knitting machine, in combination, a single guide rail having bearing surfaces on which any one of a plurality of 10 yarn-carriers is adapted to be reciprocated for distributing yarn to the needles, and a transfer mechanism having a plurality of guide rails each adapted to carry a yarn-carrier and to position any selected yarn-carrier in registration with the single guide rail so that the selected yarn-carrier may be moved back and forth upon and from one guide rail to the other, and a driver head mounted to slide on the single rail having 20 contact connection with the yarn-carrier thereon for reciprocating it in a stroke in which the yarn-carrier moves upon and between the main guide rail and a guide rail of the transfer mechanism.

25 8. In a straight knitting machine, in combination, opposed beds of needles, a single guide rail having bearing surfaces on which any one of a plurality of yarn-carriers is adapted to be reciprocated for distributing 30 yarn to the needles, and a yarn-carrier transfer mechanism at one end of the machine, said single guide rail extending beyond the active needles at the transfer end of the machine a distance sufficient to fully support 35 a yarn-carrier out of co-acting relation with the needles, said transfer mechanism having a plurality of guide rails each adapted to carry a yarn-carrier and being operable to position any guide rail in registration with 40 the single guide rail so that a yarn-carrier may be moved back and forth upon and from one transfer guide rail to the main guide rail, and vice versa, such operation of the transfer device serving to substitute one of its 45 guide rails for another in registration with the single guide rail.

9. In a straight knitting machine, in combination, a bed of needles, a plurality of 50 yarn-carriers each adapted to carry a different yarn, a single rail having bearing surfaces on which any one of said yarn-carriers is adapted to be reciprocated when in action and from one end of which the yarn-carrier is removable, a transfer device having a plurality of supplemental yarn-carrier rails 55 adapted to be positioned one at a time in alignment with and in proximity to the single rail, and means for moving a yarn-carrier from the single rail onto any supplemental 60 rail in alignment therewith.

65 10. In a straight knitting machine, in combination, a bed of needles, a plurality of yarn-carriers, a single rail having bearing surfaces on which any one of said yarn-carriers is 70 adapted to be reciprocated when in action,

a transfer mechanism having a plurality of 75 yarn-carrier rails each adapted to carry a yarn-carrier and to be positioned one at a time in alignment with the single rail, each yarn-carrier being movable from its transfer rail to the single rail and return, each yarn-carrier being reciprocable on the single rail to distribute yarn to the needles and being movable off of this rail onto a transfer rail, and the transfer mechanism being operable to substitute another transfer rail for the one in alignment with the single rail.

80 11. In a straight knitting machine, in combination, opposed beds of needles, a single guide rail having bearing surfaces on which any one of a plurality of yarn-carriers is adapted to be reciprocated for distributing 85 yarn to the needles, a driver head mounted to slide on the single rail for reciprocating the yarn-carrier thereon, and a yarn-carrier transfer mechanism at one end of the machine having a plurality of guide rails each adapted to carry a yarn-carrier and being operable to position any guide rail in registration with the single guide rail so that a 90 yarn-carrier may be moved back and forth upon and from one transfer guide rail to the single guide rail and vice versa, such operation of the transfer device serving to substitute one of its guide rails for another in 95 registration with the single guide rail, the driver head serving to reciprocate any yarn-carrier in a stroke in which the yarn-carrier moves upon and between the main guide rail and a transfer guide-rail.

100 12. In a straight knitting machine, in combination, opposed beds of needles, a single guide rail on which any one of a plurality of 105 yarn-carriers is adapted to be reciprocated for distributing yarn to the needles, a driver head mounted to slide on the single rail for reciprocating the yarn-carrier thereon, and a yarn-carrier transfer mechanism at one end of the machine having a plurality 110 of guide rails each adapted to carry a yarn-carrier and being operable to position any guide rail in registration with the single guide rail so that a yarn-carrier may be moved back and forth upon and from one transfer guide rail to the single guide rail and vice versa, such operation of the transfer device serving to substitute one of its guide rails for another in registration with the single guide rail, the driver head serving to reciprocate any yarn-carrier in 115 a stroke in which the yarn-carrier moves upon and between the main guide rail and a transfer guide rail, the transfer mechanism being operable when the driver head is at the transfer end of its stroke to substitute 120 one guide rail for another, whereby to move one yarn-carrier out of cooperative relation with the driver head and another into such relation.

125 13. In a knitting machine having opposed 130

parallel beds of needles, a single yarn-carrier rail supported in a stationary position above said beds of needles, transfer mechanism having a plurality of supplemental 5 yarn-carrier rails adapted to be respectively moved into longitudinal alignment with the stationary rail at one end thereof to form a substantially continuous support for a yarn-carrier so that it may be moved without interruption back and forth from one rail to 10 the other, a series of yarn-carriers adapted to be respectively supported on one of said supplemental rails during a non-active period and to be transferred onto the stationary rail from a position in alignment therewith for operation during an active period, 15 means for causing said transfer mechanism to position any one of its supplemental rails in alignment with the stationary rail, and 20 means for reciprocating a yarn-carrier on the stationary rail.

In witness of the foregoing I affix my signature.

WALTER F. ROLSTON.
